UNITED STATES PATENT OFFICE

EDWARD BREITWIESER, OF BUFFALO, NEW YORK

DEODORIZER FOR INCINERATORS

Application filed October 2, 1928. Serial No. 309,874.

This invention relates to a device for deodorizing the flue gases from an incinerator, and more particularly to such a device which is intended to be used in connection with household garbage and refuse incinerators so that the products of combustion of the incinerator are completely deodorized before escaping to the surrounding atmosphere.

In household refuse incinerators as heretofore constructed it has been difficult to provide an incinerator in which the obnoxious gases are completely burned and deodorized while in the combustion chamber or fire pot of the incinerator without the provision of expensive and delicate means to insure complete combustion of all the gases before leaving the fire pot. The present invention therefore proposes a simple, inexpensive and effective device for completely deodorizing the gases after they have left the combustion chamber of the incinerator, thereby permitting of employing a less expensive incinerator both in point of construction and in point of gas consumption.

25 A further object is to provide such a device which can be used in connection with any type of incinerator and in which there are no moving parts subject to the heat of the flue gases.

30 A further object is to provide such a deodorizer which will not become clogged and which can be operated economically and with a minimum consumption of gas.

In the accompanying drawings:

35 Figure 1 is a vertical section through a deodorizer embodying my invention and showing the same mounted on top of an incinerator of any usual form.

40 Figure 2 is a horizontal section, on line 2-2, Fig. 1.

Figure 3 is a horizontal section, taken on line 3-3, Figure 1.

In its general organization this invention 45 comprises a casing into which the flue gases from the incinerator are discharged, a burner surrounding the flue outlet for the incinerator and adapted to direct a plurality of flames into the path of the flue gases, and a plurality of surfaces composed of fire clay 50

or the like over which the gases must pass before escaping from the casing.

The deodorizer is shown as applied to the top 5 of an incinerator, the top 5 being formed to provide an outlet flue or stack 6 projecting upwardly from the incinerator. The deodorizer is contained within a housing or casing which is composed of a cylindrical metal wall 7, and a top 8 which is provided centrally with an outlet 9. The cylindrical wall 7 is preferably lined with a heat resistance material 10 and is bolted to the top of the incinerator in any suitable manner as by an annular ring 11 which is L-shaped in cross section and is bolted to the casing and to the top 5 of the incinerator. To attach the cylindrical wall of the deodorizer to the top of the same the top is preferably provided with a downwardly projecting annular flange 12 to which the cylindrical wall 7 is secured by means of bolts 13. The outlet 9 in the top of the deodorizer is connected to a stack 14 which conducts the deodorized gases to the exterior of the building.

At the lower end of the deodorizer a plurality of inwardly projecting brackets 15 are suitably secured to the inside of the incinerator and at their inner ends support the circular holder 16 which is filled with fire clay 17 or other similar material. As best shown in Figs. 1 and 3 the circular holder 16 is made of cast metal or the like which is formed to provide an imperforate bottom 18, a side wall 19 and an inwardly projecting annular flange 20 at the upper end of the side wall, this flange serving to retain the fire clay 17 within the holder. Suitably set into the fire clay 17 of the holder 16 are a plurality of pins or posts 21 which extend upwardly from the upper surface of the fire clay 17 and serve to support the next succeeding holder 22. The holder 22 is substantially larger than the holder 16 and at its outer side contacts with the heat resistant lining 10 of the casing so as to form a relatively tight joint therewith. The flue gases escape past this holder 22 through a central opening 23 which extends centrally therethrough. This holder 22 is formed of a cast metal shell 24 which is filled with fire clay in the same man-

ner as the holder 16. The holder 22 likewise carries pins or posts 21 which supports a third holder 25 which is similar to the holder 16, and this holder in turn supports a holder 26 similar to the holder 22 and a fifth holder 27 similar to the holder 16. By this means the flue gases upon emerging from the incinerator outlet 6 are deflected laterally by the bottom 18 of the lowermost holder 16. The flue gases thereupon pass over the fire clay 17 with which this holder is filled and escape through the central opening 24 provided in the holder 22. The gases are then deflected laterally over the fire clay contained in the holder 22 by the holder 25, and this process is continued until the flue gases have passed over the fire clay surfaces in each of the holders and escape through the outlet stack 14. By this means the holders act as baffles and the flue gases are compelled to traverse a circuitous path through the deodorizer as indicated by the arrows and are compelled to pass over the fire clay surfaces in each of the holders.

Immediately upon leaving the outlet 6 of the incinerator the flue gases are compelled to pass through or in intimate contact with a plurality of flames from a gas burner 28. As shown in Fig. 1 this burner is composed of a hollow circular portion or head 29 which surrounds the outlet 6 and is provided in an upper side with a plurality of ports 30 which direct flames against the under side of the lowermost holder 16. This head 29 is supplied with gas through a neck 31 which extends through the cylindrical wall 7 of the casing and is provided with the usual mixer 32 and gas supply pipe 33.

It is apparent that upon leaving the incinerator outlet 6 the gases from the incinerator are deflected laterally by the bottom 18 of the lowermost holder 16 and are compelled to pass through and in intimate contact with the circle of flames which are directed upwardly against the under side of the holder 16 by the burner 28. The gases are thereby heated to a comparatively high temperature of at least 400° F. and upon successively passing over the upper surfaces of the fire clay contained in the holders, heat the fire clay in these holders to substantially this same temperature. By the provision of a series of fire clay surfaces, the relatively high temperature is maintained throughout the passage of the gas through the deodorizer, and it has been found that when the flue gases are discharged from the deodorizer all of the constituents in the gases which give rise to obnoxious and objectionable odors are completely consumed. In order to insure the complete consumption of the gases auxiliary air inlet ports 34 are provided in the lower part of the casing. These ports supply air to the hot gases after the gases have passed over the burner 28 and thereby furnish the necessary supply of oxy-

gen to consume the obnoxious constituents in the gases.

It is obvious that the design can be altered very substantially without departing from the scope of my invention and that the number and the size of the various baffles or holders can be increased or diminished depending upon the conditions of incineration of the incinerator and the degree to which the deodorizing treatment is necessary.

It has been found that the deodorizer embodied in the present invention is entirely effective in removing the objectionable odors from the flue gases of incinerators and thereby completely does away with the usual foul atmosphere which follows the burning of garbage in the usual incinerator and is particularly objectionable to the neighbors. This deodorizer is also extremely simple in its operation and construction and can be produced at a very low cost thereby permitting it to be applied to standard incinerators without materially increasing the cost of the incinerating unit. The deodorizer is also durable and is not liable to clog up with soot and dirt and since it contains no moving parts is not liable to get out of order and will continue to give efficient and satisfactory service over a long period of time. The deodorizer also is very low in gas consumption and permits of a smaller gas consumption in the incinerator in view of the fact that incineration to the extent of completely deodorizing gases while in the incinerator is rendered unnecessary with the provision of this deodorizer and hence a total saving in gas consumption for the incineration of refuse or other material is effected by the present device.

I claim as my invention:

A device for deodorizing flue gases from an incinerator, comprising a casing having an inlet at its lower end, an outlet at its upper end, a burner arranged adjacent said inlet and adapted to direct a flame into the path of said gases, and two series of spaced horizontal baffles arranged in alternate relation above said inlet, each baffle of one series comprising a relatively small imperforate metal holder and a fire clay filling in said holder, and each baffle of the other series comprising a relatively large metal holder formed to provide an opening through its center and a fire clay filling in said holder, whereby the flue gases are caused to traverse a circuitous path through said casing and over the fire clay surfaces.

In testimony whereof I hereby affix my signature.

EDWARD BREITWIESER.
